UNITED STATES PATENT OFFICE.

MARIO CAMAGNI, OF PATERSON, NEW JERSEY.

TENSION LEVER.

Application filed April 30, 1928. Serial No. 273,851.

The object of this invention is to produce a tension lever of the class shown in my Patent No. 990,334 which may not only be manufactured at less cost but which is found in practice to wear longer and to produce less wear on its fulcrum pin than my patented tension lever, and in general to be more efficient in operation.

In the drawing,

10 Fig. 1 is a plan of a shuttle with the improved tension lever in place;

Figs. 2 and 3 are plans of the blank from which the lever is formed in two stages of its development;

15 Fig. 4 is a fragmentary plan of the lever, inverted;

Fig. 5 is a right-hand end elevation;

Figs. 6 and 7 are sections on lines 6—6 and 7—7, respectively; and

20 Fig. 8 is a side elevation.

In the usual cavity 1 of the shuttle body 2 is a fulcrum pin 3 for the improved tension lever (designated by the character 4 in that figure), which by an elastic band 5 is normally held retracted with respect to a line of pins or thread guides 6 so that, all in a well known way, the filling, which is threaded around these pins and alternately through guides on the lever, is normally held 25 zig-zag, the lever yielding toward the line of pins when the filling is pulled upon, as when the shuttle is in action.

The said lever is formed from a blank which comprises a strip 7 of sheet metal having at intervals pairs of opposite integral ribs 8. These ribs are all channeled, as at 9, on the same side of the blank and then bent up (as by bending the strip into channeled form lengthwise thereof) and curved with 35 their channels and concave sides toward each other, and each pair of ribs receives and holds a glass or other vitreous eyelet 10, so that each pair and the contained eyelet form one of the mentioned guides of the lever. In 40 itself so much is substantially the same as in my said patent. But in the patent the portion of the lever which formed its fulcrum or bearing and the arm for attachment of the elastic consisted of a separate piece of wire 45 bent into a coil to provide such fulcrum or bearing, with one end of the wire affording said arm and the other end forming a shank which was clinched in and by the channeled 50 end of the strip. This construction was more costly than that of my present invention, the device was heavier in weight, great

care had to be used to insure the axis of the coil being properly related to the guides in a run of levers, and the coils were not only incapable of being made always identically 60 the same but, being formed of wire, they wore away the pin 3, so that initially or ultimately the lever did not stand true in the shuttle, or it became loose at the bearing and so failed to remain true.

65 In my present construction the strip in the blank is extended, as at 11, and this extension has an additional pair of opposite ribs 12, and these are treated as now to be stated to form the bearing or fulcrum portion of the lever and its arm for attachment of the elastic.

The two ribs 12 are bent up, on lines parallel with the axis of the strip, but preferably in the direction opposite to that of bending 75 up the ribs 8, leaving a planiform portion or table 11^a between (Fig. 6). They have opposite holes 12^a formed in them and thus they afford the fulcrum portion of the lever, being adapted to receive pin 3. These holes 80 are punched in the ribs so that the material around each hole projects toward the opposite arm as a burr 12^b, thus affording an extended or surface bearing 12^c, and not a mere edge bearing.

85 The end 13 of the strip extension 11 reaches beyond the ribs 12 and this is bent up from the strip in the same direction as ribs 12, and when provided with a hole or holes 13^a will afford the arm to which the 90 elastic 5 may be connected by extending said elastic through a hole 13^a and knotting it (Fig. 1).

95 While the line of guides are preferably formed as herein described, to wit, by the channeled and bent up ribs and the (separate) eyelets 10 held thereby, it will be manifest that my invention is not concerned with the particular form or construction of the guides.

100 Having thus fully described my invention, what I claim is:

1. A tension lever for a tension device of the class described consisting of a strip of stiff sheet material having a filling guide 105 formed in part by portions projecting oppositely from the long edges of the strip and bent up in the same general direction therefrom and a pair of portions projecting from said edges of and integral with the strip and 110 bent up from the strip so as to project therefrom in the direction opposite to that in

which said first-named portions project and formed with opposite holes and thus forming the bearing of the lever.

2. A tension lever for a tension device of the class described including a strip of stiff sheet material having a pair of integral portions projecting from opposite edges of the strip and bent up from the strip in the same direction and having opposite fulcrum bearing holes punched therein and forming the fulcrum of the lever, the material displaced by the punching projecting as bearing-forming burrs.

3. A tension lever for a tension device of the class described including a strip of stiff sheet material having one end portion bent off out of the plane of the strip and forming the elastic-attaching arm of the lever and a pair of integral portions projecting from opposite sides of the strip and bent up also out of the plane of the strip in the same direction and formed with opposite holes and thus forming the bearing of the lever.

In testimony whereof I affix my signature.

MARIO CAMAGNI.
